UNITED STATES PATENT OFFICE.

MIKE HUFFMAN, OF DES MOINES, IOWA.

SEDIMENT-POCKET FOR BOILERS.

1,371,765.

Specification of Letters Patent. Patented Mar. 15, 1921.

Application filed January 13, 1920. Serial No. 351,184.

To all whom it may concern:

Be it known that I, MIKE HUFFMAN, a citizen of the United States, and a resident of Des Moines, in the county of Polk and 5 State of Iowa, have invented a certain new and useful Sediment-Pocket for Boilers, of which the following is a specification.

The object of my invention is to provide a sediment-pocket for boilers of simple, durable and inexpensive construction.

A further object of my invention is to provide a sediment-pocket for steam boilers adapted to receive the sediment therefrom, and prevent the formation of scale 15 on the boiler shell at a point where the heat from the fire box comes in contact with the shell.

A further object of my invention is to provide a sediment-pocket comprising a 20 water-leg for the boiler, extending downwardly from the lowest part of the boiler to a point below the fire box or combustion chamber, whereby the sediment may be deposited in a part of the leg, which is not 25 subject to the direct heat of the fire.

A further object of my invention is to provide such a water-leg, having novel means for reinforcing the same, and provided with an inclined bottom member, 30 whereby the sediment dropping to the bottom of the boiler will be carried by gravity down the inclined end bottom of the leg to a pre-determined point, where a blow-out opening may be provided.

35 With these and other objects in view, my invention consists in the construction, arrangement and combination of the various parts of the device, whereby the objects contemplated are attained, as hereinafter more 40 fully set forth, pointed out in my claims, and illustrated in the accompanying drawings, in which:

Figure 1 is an end elevation of a boiler, having my improved sediment-pocket installed therein, the inner wall of the fire box being removed to better illustrate the construction.

Fig. 2 is a vertical, sectional view taken adjacent to the rear end of the boiler.

50 Fig. 3 is a vertical, sectional view taken on a similar line, and illustrating a modified form of the device; and

Fig. 4 is a horizontal, central, sectional view of the device.

55 Referring to the accompanying drawings, I have used the reference numeral 10 to in-

dicate generally the rear wall of the fire box, which has side walls 11, extending upwardly to support the boiler 12, which is here shown as being a hollow, cylindrical 60 shell provided with a plurality of smoke flues 13, and having at its forward end a smoke pipe 14.

The wall of the boiler adjacent to the bottom thereof has a plurality of openings 65 15 cut therethrough in the form here illustrated, and a water-leg is extended downwardly from said openings, which is constructed as hereinafter described.

Spaced side walls 16 are held in position 70 spaced from each other by staybolts 17, and have their upper edges bent outwardly at 18 to form a flange, whereby the walls may be secured to the boiler wall.

The lower edges of the walls 16 are inclined downwardly and rearwardly from 75 their front portions and are connected by a similarly inclined bottom member 19, which has up-turned flanges 20 at either side edge, adapted to be bolted or riveted to the lower 80 edges of the walls 16.

The forward end of the bottom member 19 may be turned up to form a flange 21, whereby the flange may be secured to the bottom 85 wall of the boiler, and a water-tight connection formed between the leg and the boiler.

The rear end of the water-leg is closed by means of a wall 22, having inturned 90 flanges 23 thereon, which may be bolted or riveted to the rear edges of the walls 16.

The upper edge of the wall 22 may be turned in at 24 to form a bolted flange, whereby a water-tight connection may be made with the rear lower edge of the boiler. 95

Extended downwardly from the rear end of the water-leg is an outlet or blow-out pipe 25, which is extended through the plate 19 and forms a water-tight connection therewith. The pipe 25 is connected to an elbow 100 26 from which a nipple 27 extends rearwardly to a valve 28.

The valve 28 is disposed in a trench 29, which is connected with a sewer 30 or any other suitable means for carrying away the 105 water from the valve 29.

It will be noted that the lower rear end of the water-leg extends to position below the ground level, and consequently to position away from direct contact with the heat 110 of the combustion chamber.

In the practical operation of my im-

proved device, if the boiler 12 be filled with water, and a fire started in the grates 31, then the water in the boiler will, if the boiler is properly fired, attain a boiling point and steam be formed in the boiler.

After a definite amount of use, sediment from the water in the boiler will tend to settle toward the bottom thereof, which if it is not cleaned out will form a layer on the bottom of the boiler shell. Heat from the combustion chamber coming in contact with the lower boiler wall, where this sediment is, will eventually bake the sediment to the boiler wall, as the heat applied to the wall can not be conducted away rapidly enough by the sediment.

When this occurs, it is extremely difficult to clean the boiler. Moreover, if it is continued long enough, the boiler will burn out and an explosion will ensue. Where my improved sediment pocket is employed, however, the sediment will settle down toward the bottom of the boiler, and then down into the water leg.

In both forms of my improved water leg, the bottom thereof is inclined downwardly and rearwardly, whereby the sediment will by gravity follow the inclination of the bottom down to the portion of the leg below the ground level.

As the boiler is under pressure, it will be seen that when this lower part of the water leg is filled, then if the valve 28 is opened, the pressure of the boiler will blow the sediment adjacent to the open end of the pipe 25 out through that pipe through the elbow 26 and pipe 27 into the trench 29, where it may be carried away by the sewer 30.

Where the form of device illustrated in Fig. 3 is used, the settling of the sediment to the bottom of the water leg instead of on the bottom of the boiler shell is furthered by the inclined side plates or walls 16.

From the foregoing description, it will be seen that it would be practically impossible to burn out the bottom wall of the boiler shell where my improved sediment pocket is used, until the water leg had been filled up with sediment to position near the top thereof.

Furthermore, the sediment is all collected in one pocket, having an inclined bottom with an opening adjacent to the small end of the pocket, whereby a minimum amount of the boiler pressure and energy is required to blow a maximum amount of sediment out of the boiler.

Further the comparatively short distance between the walls 16 and the inclined bottom of the water leg makes the entire shape of the water leg, such that the maximum amount of heat is derived from the combus-

tion chamber and efficiency of the heating of the boiler is enhanced by the use of my improved sediment pocket rather than diminished.

Some changes may be made in the construction and arrangement of the parts of my improved device without departing from the essential features and purposes of my invention, and it is my intention to cover by my claims any modified forms of structure or use of mechanical equivalents, which may be reasonably included within their scope.

I claim as my invention:

1. In a boiler furnace, the combination with a boiler and suitable furnace walls, of a sediment pocket fixed to the under side of the boiler and extended downwardly and rearwardly beneath the boiler, with its bottom arranged at such a steep incline that sediment within the sediment pocket will move by gravity downwardly and rearwardly, the said boiler being provided with suitable openings in its bottom to provide for the passage of sediment from the boiler into the sediment pocket, the lower rear portion of the sediment pocket being extended downwardly inside of the furnace walls to a point where the heat from the furnace will not substantially affect it, and the rear of the sediment pocket being spaced from the rear wall of the furnace far enough to permit the circulation of the products of combustion beyond the rear of the sediment pocket, where it may return through the boiler, and a blow-off valve at the lower portion of the sediment pocket, for the purposes stated.

2. The combination with a cylindrical boiler, of a sediment pocket attached thereto, said boiler being provided at its bottom with transversely arranged slotted openings through which sediment may be discharged, the boiler portions between the slots being so arranged as to provide braces for the boiler against internal pressures, and said sediment pocket comprising two side sheets and a bottom portion, said side sheets having their upper edges riveted to the boiler along its sides and above the slots, said bottom being inclined downwardly and rearwardly at such an angle as to cause sediment in the boiler to flow by gravity to the rear lower end of the sediment pocket, and blow-off valve at the bottom of the sediment pocket, and a series of bolts passed through the sides of the sediment pocket to brace said sediment pocket against internal pressures, for the purposes stated.

Des Moines, Iowa, December 29, 1919.
MIKE HUFFMAN.
